UNITED STATES PATENT OFFICE.

AUGUSTE NAMUR, OF NEW YORK, N. Y., ASSIGNOR TO THE TUTTLE & BAILEY MANUFACTURING COMPANY, OF SAME PLACE.

DESIGN FOR A REGISTER-FRONT.

SPECIFICATION forming part of Design No. 15,275, dated August 19, 1884.

Application filed April 5, 1884. Term of patent 14 years.

To all whom it may concern:

Be it known that I, AUGUSTE NAMUR, a citizen of Luxemburg, Germany, residing at New York city, county and State of New York, have invented and produced a new and original Design for Hot-Air-Register Fronts, of which the following is a specification.

My design for hot-air-register fronts is represented in two views by the accompanying photograph in front elevation; and it consists of the center flower device, *a*, surrounded by the flamboyant device *b*, with arched panels *c*, having flower and leaf devices *d* traversing the arches, said arches and figure *b* being separated by the parallel and cross-bar devices *e*, and surrounded or partly surrounded by a diamond border, *f*, with leaf figures *g* and plain bar *h*. The diamond border *f* is surrounded by parallel plain bars *i*, connected by curved cross-bars *j*, and the whole is surrounded by a raised Grecian Roman border-figure, *k*, on a plain ground between the plain bead *l* and the outer plain bar, *m*.

The center devices, *a* and *b*, may be used with other exterior figures or devices, and either on a rectangular frame or one with an oval top. The arch-panels may also be used on a front plate of oval form at the top.

What I claim is—

1. The design for a register-front, consisting

of the center flower device, *a*, surrounded by the flamboyant device *b*, and a border surrounding the same.

2. The design for a register-front, herein shown, consisting of the center flower device *a*, surrounded by the flamboyant device *b*, with arched panels *c*, having flower and leaf figures *d*, traversing the arches separated from said figures *b* by the parallel and cross-bar devices, and surrounded or partly surrounded by a diamond border, *f*, with leaf figures *g* and plain bars, *h*.

3. The design for a register-front, herein shown and described, consisting of the center flower device, *a*, surrounded by the flamboyant device *b*, with arched panels *c*, having flower and leaf figures *d*, traversing the arches, separated from said figures *b* by the parallel and cross-bar devices *e*, and surrounded or partly surrounded by the diamond border *f*, with leaf figures *g* and plain bars *h*, and the whole being inclosed by a raised Grecian Roman border having figures *k* on a plain ground between the plain bead *l* and the outer plain bar, *m*.

AUGUSTE NAMUR.
